SUCTION-INTENSIFYING CARBURETER.

1,191,156.

Specification of Letters Patent. Patented July 18, 1916.

Application filed August 14, 1913. Serial No. 784,697.

REISSUED.

To all whom it may concern:

Be it known that we, ERNEST F. CIGLIA and LOUIS F. PELLETIER, citizens of the United States, residing at New York city, in the county of New York and State of New York, have invented certain new and useful Improvements in Suction-Intensifying Carbureters, of which the following is a specification.

10 The object of our invention is to provide an efficient and economical carbureter in which the fuel and air are properly mixed and the quantities thereof are simultaneously and positively regulated by throttling devices which respectively control the area 15 of the fuel nozzle and the air inlets.

In the drawings Figure 1 is a plan; Fig. 2 a sectional plan on the line 2—2 of Figs. 3, 4 and 5. Fig. 3 an inlet face elevation partly in section, Fig. 4 a side elevation reading with Fig. 1; Fig. 5 a vertical section on the line 5—5 of Figs. 1, 2 and 3 and Fig. 6 an eccentric section at the same line, illustrating tubular air-supply regulating members.

25 As illustrated the shell 1 is a tubular casting containing a vertical, open-ended, substantially cylindrical bore 10 and a segmental fuel reservoir 11 concentric with and adjacent to the lower part, and slightly more 30 than half the height of said bore, and cast with an open top, which is closed with a sheet metal cap 12. The reservoir has an extension 13 provided with a union 14 for attaching the fuel pipe 15 and containing a 35 valve connected therewith and operated by the float *f* to control the fuel-supply, in the usual mode.

Opening into the bore 10 preferably at 40 right angles with the reservoir and a suitable distance below its top is a converging right conical Venturi inlet 30, from whose throat the shell is slotted to form guides 16 for a reciprocating regulating apparatus generally indicated by 5; and at right angles 45 therewith, diametrically opposite the reservoir 11, is a rack-recess 17, whose outer wall is slotted between a pair of bosses 18, inwardly from which are formed outstanding stops, 19, the purposes of which will be explained.

50 Fuel is supplied from the reservoir through a suitable passage 20, drilled in the shell and extending from a boss 21, in the reservoir floor, to the nozzle 22 which extends nearly half way across the Venturi throat into the area of the maximum air-

velocity and suction thereby induced as is the known action of Venturi tubes; and whose delivery is controlled by a needle 23, operably mounted on said regulating apparatus 5 and thereby reciprocated in said nozzle to enlarge and contract its delivery area.

The air supply members comprise a Venturi tube 3, which is bent substantially at a right angle and is made of two separated parts, viz:—its said inlet cone 30 and its delivery part 31, which has a foraminous wall 32, terminates at its outlet in a positioning flange 33; whose throat is at right angles thereto and whose passage is horn-like and bends and expands from its throat to merge into a substantially semi-ellipsoidal mixing and delivery chamber, 34.

The Venturi delivery part 31 is located axially in the bore 10 by means of a flanged and shouldered open ended tube 35 somewhat smaller than and extending through the bore 10, fastened to its wall, surrounded by an annular space, and provided with an opening 36 which forms part of the Venturi throat, and a shouldered upper end terminating in a flange 37 containing bolt-holes 38 by means of which the carbureter is fixed in place.

Supplemental registering air inlets, 38 are 85 formed in convenient locations, somewhat lower than the Venturi throat, in the walls of the tube 35, bore 10, and a box 40, to be described.

The throat end of the Venturi delivery 90 part 31 and the flange 33 thereof respectively fit the wall of said tube 10 about its opening 36 and in a recess formed in its flange 37, to which the flange 33 is screwed.

A supplemental air supply valve 39 is located in the lower part of the tube 35 and is mounted on a cylindrical box 40 whose inner head contains the port 41 controlled by said valve and whose outer head 42 is preferably detachable to facilitate assembling and extends on and is fastened to the end of the shell 1, to secure the box 40 and valve 39 in place. Said valve is a puppet of usual construction, screwed on a threaded stem 43, locked in adjusted position by lock nuts and seated by a spring 44.

A tubular throttle valve 50 is mounted on the tube 31, adapted to cover and uncover the supplemental air inlets 38 and control the supply of air to the valve 39 and provided with a key-hole-shaped port consisting of a circular port 45 corresponding with

the Venturi throat and an upwardly extending graduated, converging extension 46 thereof; a guide head 51 in line with said port and containing a hole in which the 5 needle 23 is adjustably mounted and fixed in adjusted position by a set screw 24; and at right angles thereto a rack 52 for reciprocating the throttle 50 and needle 23 and simultaneously and proportionally controlling the air and fuel supplies. The apparatus 5 which accomplishes such regulation comprises the throttle, and rack 52, a pinion segment 53, meshed therewith and fixed to a shaft 54 mounted in the bosses 18, revoluble 15 by means of a lever 55, and limited in its stroke by an arm 56 and adjustment screw 57 therein, adapted to contact with one of the stops 19. The shaft 54 is illustrated as symmetrical, adapted for the attaching, at 20 either end thereof, the arm 56 and lever 55; and the angular locations of the latter relatively to the pinion 53 is made adjustable by forming pluralities of clutch members or teeth 59 on the contact faces of said lever 25 and arm, locating the lever as desired and binding it, by nuts 58, to the arm, with the teeth engaged. A cover, 160, is bolted on the shell 1 over the guide slot and needle.

The operation of the carbureter is as follows: Fuel supplied through the pipe 15 is admitted to and its stand is regulated in the reservoir 11 by the float *f* and valve connected therewith; and by means of the channel 20 it passes to and stands in the nozzle 35 22 nearly up to its outlet. Air drawn in through the venturi 3 draws fuel out of the nozzle 22 and forms with it an explosive mixture. When the engine is running under normal conditions, with its rated load, 40 the lever 55, throttle 50 and needle 23 are located in the positions shown in full lines in Fig. 3, and the fuel supply through the nozzle 22 is practically free; the Venturi throat and the supplementary air openings 45 are not obstructed by the throttle 50 and the aspiration of the engine draws in a maximum supply of fuel and as much air through the venturi as it can admit; and at the same time draws in supplemental air through the 50 openings 18, valve 39, the spaces about the tube 35 and Venturi delivery part 31 and the foraminous wall, 32 of the latter; and the arrangement of the ports and the admission of supplemental air through its 55 foraminous wall, cause the explosive mixture to be as lean as it is practicable to fire in a hot engine. When the engine is being started the lever 55, throttle 50 and needle 23 are moved approximately to mean position, as shown in Fig. 6; the supplemental air inlets 38 are covered by the throttle and the circular port 45 partly throttles the Venturi throat. No air can be drawn through the supplemental inlets and valve and the 60 entire air supply is drawn through the ven-

turi, and being forced by the position of the throttle to flow in a contracted current of high velocity across the outlet of the fuel nozzle, sucks therefrom a relatively large fuel supply and forms therewith a rich mixture, well adapted to be fired in a cold engine. 70

When the engine is running idly the lever 55 is located at the opposite limit of its stroke, the throttle 50 is fully advanced and covers the supplemental air inlets 38, as indicated in dotted lines in Fig. 3, the Venturi port 45 is out of register with the Venturi throat and the tip of the contracted port-extension 46 extends slightly above the center 80 of the Venturi throat and the outlet of the fuel nozzle 22 which is reduced to its minimum discharge area by the advance of the needle 23. Under such circumstances no air whatever can be drawn in through the supplemental inlets and only the minimum quantity through the unobstructed portion of the contracted port 46; but part of this air draws directly across the outlet of the fuel nozzle, sucks the minimum quantity of 90 fuel therefrom and forms therewith an explosion mixture sufficient to turn the engine idly. 85

When the engine is stopped the parts are 95 located nearly as above described but slightly more advanced so that the needle 23 will entirely close the nozzle 22 and prevent any loss of fuel at such times.

When the engine is running under light and varying loads the operator can economize fuel and secure its perfect combustion by varying the position of the lever 55 proportionally to the necessity for power. 100

The Venturi tube part of a fluid conduit causes the mean velocity of fluid flowing 105 through its throat to become several times the mean velocity in the conduit and to equal, or even exceed, and the maximum velocity therethrough to considerably exceed, the theoretical velocity of discharge of such fluid from a reservoir due to a pressure equal to the loss of head. By locating the outlet of the fuel nozzle 22 substantially 110 in the area of maximum velocity, in the Venturi throat, we obtain the maximum 115 suction on the fuel possible with a given engine suction.

As air coming at high velocity from the Venturi throat flows through and fills the expanding Venturi delivery part 31 its velocity is reduced inversely proportionally to the area of the latter, correspondingly expends its momentum in dilation and causes suction on its foraminous wall 32, without waste of power and draws through 125 it the supplemental air supply when the throttle 50 is open. The same power, engine suction and kinetic energy of the incoming air which is necessary to suck in the fuel, subsequently sucks in the supplemen- 130

tary air. Therefore our carbureter effects a considerable increase in the power and in the percentage of efficiency, of engines to which it is applied. It does this by supplying perfect explosive mixtures at varying engine speeds and by making it possible to enlarge the supply ports and conduits and thereby reduce the back pressure and negative work of the engine.

10 As illustrated in dotted lines, Fig. 3, when the engine is running idly, all the air-supply ports are closed save that the throat port extension 46 is so adjusted that the sole air supply is drawn through its upper position and directly across the outlet of the fuel nozzle 22. Thus concentrating the air supply gives it high velocity so that it will suck in sufficient fuel to make a reliable explosive mixture. At the same time its volume 15 is so small that it will only develop enough power to turn the engine idly, at low speed.

We claim as new and desire to protect by Letters Patent:

1. In a carbureter for explosion engines, 25 a shell containing a fuel reservoir connected with a fuel supply and a fuel nozzle and containing a float adapted to regulate the supply of fuel; a tubular wall of said shell forming a tubular passage and formed with 30 guides and openings as hereinafter referred to; an inner tube smaller than, located in, and closing the end of said passage, and formed with openings as hereinafter referred to; a Venturi tube bent substantially 35 through a right angle, having its throat substantially coinciding with an opening formed therefor in said inner tube, its inlet cone connected with an opening in said tubular wall, the fuel nozzle opening into its throat and its delivery port located in said inner tube and formed with a foraminous wall; a diaphragm in said inner tube exterior to said venturi and containing a supplemental air port; a spring seated valve 40 co-acting with said port; a cap closing the end of said tube exterior to said diaphragm and valve; said tubular wall and inner tube being formed with supplemental air inlets between said diaphragm and cap; a tubular 45 throttle valve mounted on said inner tube, adapted to cover and uncover said inlets and formed with a circular port adapted to register with the Venturi throat opening in said inner tube and having a graduated 50 tapered extension, a guide head formed on said throttle adapted to co-act with the guides of said tubular wall, a needle valve connected with said throttle adapted to throttle the outlet of the fuel nozzle, and 55 means to reciprocate said tubular throttle valve.

2. In a carbureter for explosion engines, 60 a shell containing a fuel reservoir connected with a fuel supply and a fuel nozzle and containing a float adapted to regulate the

supply of fuel; a tubular wall of said shell forming a tubular passage and formed with guides and an opening as hereinafter referred to; an inner tube smaller than, located in, and closing one end of said passage and formed with an opening as hereinafter referred to; a Venturi tube bent substantially through a right angle, having its throat substantially coinciding with an opening formed therefor in said inner tube, 70 its inlet cone connected with an opening in said tubular wall, the fuel nozzle opening into its throat and its delivery port located in said inner tube; a tubular throttle valve mounted on said inner tube, formed with a circular port adapted to register with the Venturi throat opening in said inner tube and having a graduated, tapered extension, a guide head formed on said throttle adapted to co-act with guides of said tubular wall, 80 a needle valve connected with said throttle adapted to throttle the outlet of the fuel nozzle, and means to reciprocate said tubular throttle valve.

3. In a carbureter for explosion engines 90 comprising a shell containing a fuel reservoir connected with a fuel supply and a fuel nozzle and containing a float adapted to regulate the supply of fuel, the combination therewith of a tubular wall of such 95 shell forming a tubular passage and formed with a slot whose edges form guides, an axially extending recess and openings as hereinafter referred to; an inner tube, smaller than, located in and closing one end of such passage and formed with an opening hereinafter referred to; a Venturi tube bent substantially through a right angle, having its throat substantially coinciding with an opening formed therefor in said inner tube, its inlet cone connected with an opening in said tubular wall and the fuel nozzle extending into it and its delivery port located in said inner tubes, a throttle 100 valve mounted on said inner tube, engaging said guides and adapted to regulate the passage of air through said Venturi tube and operating means operably connected with said throttle valve.

4. In a carbureter for explosion engines, 115 comprising a shell containing a fuel reservoir connected with a fuel supply and a fuel nozzle and containing a float adapted to regulate the supply of fuel, the combination therewith of a tubular wall of such shell forming a tubular passage and formed with a slot whose edges form guides, an axially extending recess and openings as hereinafter referred to; an inner tube, smaller than, located in and closing one end of such passage and formed with an opening hereinafter referred to; a Venturi tube bent substantially through a right angle, having its throat substantially coinciding with an opening formed therefor in said inner tube, 120 125 130

its inlet cone connected with an opening in said tubular wall and the fuel nozzle extending into and its delivery part located in said inner tube, a tubular throttle valve 5 mounted on said inner tube, formed with a circular port adapted to register with the Venturi throat and a graduated extension of said port, on said throttle a head engaging said guides, and a rack, a pinion engaging 10 said rack, extending through an opening in said tubular wall and fixed on a shaft revolvably mounted in said wall, and fixed to said shaft a lever and a graduating screw adapted to engage a fixed stop and limit the 15 stroke of said throttle.

5. In a carbureter for explosion engines, comprising a shell containing a fuel reservoir connected with a fuel supply and a fuel nozzle and containing a float adapted to 20 regulate the supply of fuel, the combination therewith of a tubular wall of such shell forming a tubular passage and formed with a slot whose edges form guides, an axially extending recess and openings as hereininafter referred to; an inner tube, smaller than, located in and closing one end of such passage and formed with an opening hereininafter referred to; a Venturi tube bent substantially through a right angle having its 25 throat substantially coinciding with an opening formed therefor in said inner tube, its inlet cone connected with an opening in said tubular wall and the fuel nozzle extending into it and its delivery port located 30 in said inner tube, a tubular throttle valve mounted on said inner tube, formed with a circular port adapted to register with the Venturi throat and a graduated extension of 35 said port; on said throttle a head engaging said guides, and a rack, a pinion engaging 40 said rack, extending through an opening in said tubular wall and fixed on a shaft revolvably mounted in said wall; an arm fixed to said shaft, a graduating screw in said arm adapted to engage a fixed stop and limit the 45 stroke of said throttle, a lever on said shaft and clutch formations on said arm and lever adapted to engage them in adjusted angular 50 relations.

6. In a carbureter for explosion engines comprising a shell containing a fuel reservoir connected with a fuel supply and a fuel nozzle and containing a float adapted to 55 regulate the supply of fuel, the combination therewith of a tubular wall of such shell forming a tubular passage with an axially extending recess and a slot therein, adjacent thereto a shaft support and a stop, a tubular valve operable in said passage and having a 60 member playing in said recess, valve shifting means mounted in said shaft-support and coacting with said valve and stroke-adjustment means on said shifting means and adjustable relatively to said stop.

65 7. In a carbureter comprising a shell con-

taining a fuel reservoir connected with a fuel supply and a fuel nozzle and containing a float adapted to regulate the supply of fuel, the combination therewith of a bent Venturi tube whose delivery port has a foraminous wall and having the fuel nozzle opening substantially into its throat. 70

8. In a carbureter adapted to be connected with a chamber in which pressure less than atmosphere periodically obtains and comprising a fuel reservoir connected with a fuel supply, a fuel nozzle and a float adapted to regulate the supply of fuel, the combination therewith of suction intensifying apparatus comprising a Venturi tube communicating with the atmosphere by its inlet cone and by its delivery cone with said chamber, having the fuel nozzle opening into its throat and, adjacent to its throat, a foraminous section in the wall of its delivery cone. 80

9. In a carbureter adapted to be connected with a chamber in which pressure less than atmosphere periodically obtains and comprising a fuel reservoir connected with a fuel supply, a fuel nozzle and a float adapted to regulate the supply of fuel, the combination therewith of suction intensifying apparatus comprising an air supply conduit communicating with said chamber; a Venturi tube located in and having the wall of 95 its delivery cone joined to the wall of said conduit, its inlet cone communicating independently with the atmosphere, the fuel supply nozzle opening into its throat, and, adjacent to its throat, a foraminous section in the 100 wall of its delivery cone; and a valve controlling the admission of air to said conduit exterior to said Venturi tube. 100

10. In a carbureter adapted to be connected with a chamber in which pressure less than atmosphere periodically obtains and comprising a fuel reservoir connected with a fuel supply, a fuel nozzle and a float adapted to regulate the supply of fuel, the combination therewith of suction intensifying apparatus comprising an air supply conduit 105 communicating with said chamber; a Venturi tube located in and having the wall of its delivery cone joined to the wall of said conduit, its inlet cone communicating independently with the atmosphere, the fuel supply nozzle opening into its throat, and, adjacent to its throat, a foraminous section in the 110 wall of its delivery cone; a valve controlling the admission of air to said conduit exterior to said Venturi tube; and a check valve between the aforesaid valve and said Venturi tube. 115

11. In a carbureter adapted to be connected with a chamber in which pressure less than atmosphere periodically obtains and comprising a fuel reservoir connected with a fuel supply, a fuel nozzle and a float adapted to regulate the supply of fuel, the combination therewith of suction intensifying 120

125

apparatus comprising an air supply conduit communicating with said chamber; a Venturi tube located in and having the wall of its delivery cone joined to the wall of said conduit, its inlet cone communicating independently with the atmosphere, the fuel supply nozzle opening into its throat, and, adjacent to its throat, a foraminous section in the wall of its delivery cone; a valve controlling the admission of air to said conduit exterior to said Venturi tube; and a graduating valve controlling the throat of said Venturi tube.

12. A carbureter for explosion engines comprising a shell containing a fuel reservoir connected with a fuel supply and containing a float adapted to regulate the supply of fuel, a Venturi tube, a fuel nozzle connected with said fuel reservoir and opening into said Venturi's throat, a valve operable to regulate the volume of air flowing through said Venturi throat and having a port substantially coinciding with the opening of said throat when in register therewith, said port having a narrow extension adapted, when the valve is shifted, to direct the supply of air flowing through said Venturi throat directly by the outlet of said fuel nozzle, a needle valve connected with said first named valve and coacting with the outlet of said fuel nozzle.

13. In a carbureter for explosion engines comprising a tubular shell having a fuel nozzle connected with a fuel supply, an inner tube in said shell closing one end of said tubular shell, there being an opening in said tubular shell and there being an opening in said inner tube registering with one another, a Venturi tube having its throat substantially coinciding with the opening formed in said inner tube, the fuel nozzle extending across the outside of the throat of said Venturi tube, a throttle valve mounted on said inner tube to regulate the passage of air through said Venturi tube, and operating means for said throttle valve.

14. In a carbureter for explosion engines comprising a tubular shell having a fuel

nozzle connected with a fuel supply, an inner tube in said tubular shell closing one end of said tubular shell, there being an opening in said tubular shell and there being an opening in said inner tube registering with one another, a Venturi tube having its throat substantially coinciding with the opening formed in said inner tube and its delivery end disposed in said inner tube, the fuel nozzle extending across the outside of the throat of said Venturi tube, a tubular throttle valve slidably mounted between said inner tube and said shell, a needle on said valve registering with said fuel nozzle, and means for operating said tubular valve to regulate the passage of air into said Venturi tube and the passage of fuel through said fuel nozzle.

15. In a carbureter for explosion engines comprising a tubular shell having a fuel nozzle connected with a fuel supply, an inner tube in said tubular shell closing one end of said tubular shell, there being an opening in said tubular shell and there being an opening in said inner tube registering with one another, a Venturi tube having its throat substantially coinciding with the opening formed in said inner tube and its delivery end disposed in said inner tube, the fuel nozzle extending across the outside of the throat of said Venturi tube, a tubular throttle valve slidably mounted between said inner tube and said shell, a needle on said valve registering with said fuel nozzle, and means for operating said tubular valve to regulate the passage of air into said Venturi tube and the passage of fuel through said fuel nozzle, said operating means comprising a rack on said tubular valve, a pinion engaging said rack, and means actuating said pinion to actuate said tubular valve.
